CLAIM

We claim the ornamental design for a handheld skin exfoliator, as shown and described.

DESCRIPTION

FIG. 1 is a front isometric view of a first embodiment of a handheld skin exfoliator.

FIG. 2 is a rear isometric view of the handheld skin exfoliator of FIG. 1.

FIG. 3 is a front elevation view of the handheld skin exfoliator of FIG. 1.

FIG. 4 is a rear elevation view of the handheld skin exfoliator of FIG. 1.

FIG. 5 is a left side elevation view of the handheld skin exfoliator of FIG. 1.

FIG. 6 is a right side elevation view of the handheld skin exfoliator of FIG. 1.

FIG. 7 is a top plan view of the handheld skin exfoliator of FIG. 1.

FIG. 8 is a bottom plan view of the handheld skin exfoliator of FIG. 1; and,

FIG. 9 is an enlarged front elevation view of the handheld skin exfoliator of FIG. 1 and taken along detail 9 of FIG. 3. The dot-dash lines shown in FIGS. 3 and 9 indicate the bounds of the enlarged detail view of FIG. 9 and do not form a part of the claimed design. The evenly-incremented broken lines illustrate features of the article of manufacture that form no part of the claimed design.
